UNITED STATES PATENT OFFICE.

ROBERT J. BENNETT, OF MOLINE, ILLINOIS, ASSIGNOR TO ARTISTA PIANO PLAYER COMPANY, OF MILAN, ILLINOIS, A CORPORATION OF ILLINOIS.

FOLDING TREADLE FOR PIANO-PLAYING ATTACHMENTS.

984,527.

Specification of Letters Patent. Patented Feb. 21, 1911.

Application filed October 27, 1909. Serial No. 524,887.

To all whom it may concern:

Be it known that I, ROBERT J. BENNETT, a citizen of the United States, residing at Moline, in the county of Rock Island and State 5 of Illinois, have invented certain new and useful Improvements in Folding Treadles for Piano-Playing Attachments, of which the following is a specification.

This invention relates to improvements in 10 folding treadles for piano playing attachments adapted to be folded into the casing through an opening therein when not in use and one of the objects of the invention is to provide improved means whereby the treadle 15 and operating mechanism may be readily detached from the operating mechanism for the wind inducing or suction bellows when desired.

A further object is to provide improved 20 mechanism of this character which will be simple in construction and which when folded into the casing will be compact and will occupy a minimum space.

To the attainment of these ends and the 25 accomplishment of other new and useful objects, as will appear, the invention consists in the features of novelty in the construction, combination and arrangement of the several parts hereinafter more fully described and 30 claimed and shown in the accompanying drawings illustrating an embodiment of the invention, and in which—

Figure 1 is a sectional view taken on line 1—1 of Fig. 3 of an improved device of this 35 character constructed in accordance with the principles of this invention. Fig. 2 is a sectional view on line 2—2 of Fig. 1. Fig. 3 is a sectional view on line 3—3 of Fig. 1. Fig. 4 is a view similar to Fig. 3 showing the 40 treadle attachment folded into the casing of a musical instrument.

Referring more particularly to the drawings and in the present exemplification of the invention the numeral 10 designates the portion 45 of a musical instrument to which this improved attachment is applied and the casing is provided with an open front adjacent the bottom thereof. Within the casing and adjacent each side thereof are located 50 a pumper or suction creating devices 11 in the form of pneumatics or bellows. Each of these bellows is supported in position in any desired or suitable manner and is arranged so that one of the members of the bellows 55 will be disposed toward the rear of the in-

strument and in a position to swing in an upright plane. An elastic member 12, preferably in the form of a spring, is provided which is disposed between the movable member of the bellows and a fixed support, and 60 these springs tend normally to collapse the bellows.

Arranged within the casing at the base thereof and spaced longitudinally from each other are rock shafts 13, each of which 65 is journaled in suitable bearings 14 and the adjacent extremities of the shafts extend beyond the adjacent bearings 14 and are journaled in bearings 15 which are spaced from the respective bearings 14. Each of the 70 rock shafts 13 is provided with a crank arm 16 adjacent the respective bellows 11 and journaled to the free extremity of each of the crank arms is an anti-friction roller 17 which is adapted to engage a projection 18 75 secured to the inovable member of the bellows, so that when the shaft is rocked to move the crank arm 17 toward the rear of the casing, the movable member of the bellows will be moved to cause the bellows to 80 expand against the tension of the elastic member 12. When pressure on the crank arm is released, the elastic member will collapse the bellows.

A treadle support is provided adjacent the 85 inner extremities of the rock shaft 13 and this support comprises two pairs of spaced members 19 which are connected at their free extremities by means of a connecting bar or member 20. These members 19 are 90 provided with bifurcated extremities 21 which are adapted to removably engage the portion of the respective rock shafts 13 between the bearings 14 and 15, which latter serve as means for preventing displacement 95 of the members longitudinally with respect to the rock shafts. The free extremities of the members 19 are provided with feet 22 which are adapted to engage and rest upon the floor. These members 19 may be of any 100 desired length and of any desired configuration and the rear ends thereof are preferably bent upwardly as shown. Secured to each of the rock shafts 13 and intermediate the bifurcated extremities 21 of the respective pairs 105 of the members 19 is a crank arm 23, which is preferably disposed in the opposite direction from the crank arms 17. These crank arms 23 are preferably provided with a bifurcated extremity into which one ex- 110

tremity of a member 24 projects and is removably secured to the crank arm 23, in any desired or suitable manner, preferably by means of a fastening device 25 such as a pin 5 or the like, passing through the crank arm 23 and the extremity 24, and a cotter pin 26 may be provided for preventing accidental displacement of the fastening device 25.

The extremity of the member 24 adjacent 10 the end which is secured to the crank arm 23 is arched as at 27 so as to extend over the rock shaft 13. The forward end of the member 24 is deflected downwardly and extends through a suitable opening in the toe 15 rail 28. This member 24 is arranged between the pair of members 19 and is supported by means of a pair of links 29, one extremity of each of which is pivotally connected as at 30 to the member 24 and the 20 other extremity of the links are connected as at 31 to the members 19. These links 29 preferably incline forwardly as shown. The free extremity of the member 24 terminates short of the connecting member 20 of the 25 pairs of members 19 and an anti-friction roller 32 is journaled in the free extremity of the member.

Treadles 33 are pivotally supported by their forward extremities to the connecting 30 member 20 of the pairs of members 19. Depending from the lower face of each of the treadles is a projection 34 which has an inclined lower face 35 and this face is adapted to engage and rest upon the roller 32 of 35 the respective members 24, and the depending portions 34 of the treadles are so located that when the bellows 11 is collapsed, the treadle will be held in an elevated position for use. When pressure is exerted upon the 40 treadle 33 it will move about its point of pivotal support and the extension 34 will be depressed to cause the inclined face 35 to ride over the roller 32, which movement will cause the member 24 to swing backwardly 45 upon the supporting links 29 to rock the shaft 13 and expand the bellows. By providing the links 29 the members 24 will be supported for a free oscillating movement.

When the treadles are not in use, the 50 members 19 may be swung about their points of pivotal connection with the shafts 13, which will cause the members 24 to swing about their points of pivotal connections with the crank arms 23 to permit the treadles 55 to be folded into the casing. As the supports and treadles move inwardly into the casing, they will assume the positions shown in Fig. 4, that is, the depending portion 34 will move away from the anti-friction roller 60 32 and the member 24 and the treadles will be supported so as to hang in upright positions from their points of pivotal connection with the supporting frame.

When it is desired to remove the treadle 65 attachment all that is necessary is to remove

the fastening devices 25 to disconnect the members 24 from the crank arms 23, after which the entire treadle mechanism, including the treadles, and operating members 24, may be readily detached and removed, leaving only the rocker shafts and their supports and the crank arms 16 which operate the bellows.

In order that the invention might be fully understood the details of the foregoing embodiment thereof have been thus specifically described, but what is claimed as new is—

1. In a folding pedal mechanism, the combination of a treadle support pivoted at its inner end to a fixed support, a rock shaft, 80 a bellows, an operative connection between the shaft and bellows, an operating member, a link supporting said member intermediate its ends and from the treadle support for bodily oscillating movement, an operative 85 connection between the member and the shaft, a treadle pivotally mounted on the support, the free end of the said operating member terminating adjacent the treadle, and means on the treadle adapted to engage 90 the free end of the member to oscillate the same to rock the shaft, said treadle support and operating member being movable respectively about their points of connection with a fixed support and shaft during folding and unfolding movements.

2. In a folding pedal mechanism, the combination of a treadle support pivoted at its inner end to a fixed support, a rock shaft, a bellows, an operative connection between the 100 shaft and bellows, an operating member, a link pivotally supporting the member intermediate its ends and from the treadle support for bodily oscillating movement, an operative connection between the member and the shaft, a treadle pivotally mounted on the support, one end of said operating member terminating adjacent the treadle, and a cam on the treadle adapted to engage 105 and move over the end of the operating member to oscillate the same to rock the shaft, said treadle, support and operating member being movable respectively about their points of connection with the said fixed support and shaft during folding and unfolding movements.

3. In a folding pedal mechanism, the combination of a treadle support pivoted at its inner end to a fixed support, a rock shaft, a bellows, an operative connection between the 120 shaft and bellows, an operating member, a link pivotally supporting the member intermediate its ends and from the treadle support for bodily oscillating movement, an operative connection between the member and the shaft, a treadle pivotally mounted on the support, one end of said operating member terminating adjacent the treadle, a roller on the said end of the operating member, and a cam on the treadle adapted to en- 125 130

gage and move over the roller to oscillate the operating member to rock the shaft, said treadle support and operating member being movable respectively about their points 5 of connection with the said fixed support and shaft during folding and unfolding movements.

4. In a folding treadle mechanism, the combination of a treadle support detachably pivoted at its inner end to a fixed support, a rock shaft, a bellows, an operative connection between the shaft and bellows, an operating member, means supporting said member intermediate its ends and from the 15 treadle support for longitudinal oscillatory movement, a detachable operative connection between the member and the shaft, and a treadle pivotally mounted on the treadle support, the free end of the operating member 20 terminating adjacent the treadle and adapted to be engaged and oscillated thereby.

5. In a folding treadle mechanism, the combination of a treadle support detachably pivoted at its inner end to a fixed support, 25 a rock shaft, a bellows, an operative connection between the shaft and bellows, an operating member, a link supporting said member intermediate its ends and from the treadle support for bodily oscillatory movement, a treadle pivoted to the support adapted 30 to engage and oscillate said member, a crank on the shaft, and a fastening device for connecting the said operating member and the crank, said fastening device also 35 serving to hold the parts assembled and adapted to be removed to permit the treadle support, operating member and treadle to be detached.

6. In a folding treadle mechanism, the 40 combination of a rock shaft, a treadle support comprising spaced coöperating members pivotally connected to the shaft at their inner ends, and for independent movement with respect to the shaft, an operating member disposed between the first said members, a link pivotally supporting said operating member intermediate its ends and from the treadle support, a crank on the shaft, means connecting one end of the 45 operating member with the crank, a treadle pivotally mounted on the support, the free end of the operating member terminating adjacent the treadle and means on the treadle detached from and engaging said 50 operating member to operate the latter when the treadle is operated, said operating member also serving to hold the treadle in position for use.

7. In a folding treadle mechanism, the 60 combination of a rock shaft, a treadle support comprising a member having a bifurcated extremity engaging the shaft for detachably connecting the member to the shaft for pivotal movement independently with 65 respect to the shaft, an operating member,

a link pivotally supporting the latter intermediate its ends and from the treadle support, a treadle pivotally mounted on the support, one end of said operating member terminating adjacent the treadle and detached therefrom, said treadle being adapted to engage and operate said operating member, and a detachable pivotal connection between the operating member and the shaft, said connection serving to hold the 70 parts assembled, the treadle support, treadle and operating member being adapted to be removed when said connection is detached.

8. In a folding treadle mechanism, the combination of a rock shaft, a treadle support comprising a member having a bifurcated extremity engaging the shaft for detachably connecting the member to the shaft for pivotal movement independently with respect to the shaft, an operating member, 80 a link pivotally supporting the latter intermediate its ends and from the treadle support, a treadle pivotally mounted on the support, one end of said operating member terminating adjacent the treadle and being 85 detached therefrom, said treadle being adapted to engage and operate said operating member, a crank on the shaft, means detachably and pivotally connecting the said operating member with the crank, said 90 connecting means serving to hold the parts assembled and permitting the removal of all 95 of the parts when detached.

9. In a folding treadle mechanism, the combination of a rock shaft, a treadle support comprising a member having a bifurcated extremity engaging the shaft for detachably connecting the member to the shaft for pivotal movement independently with respect to the shaft, an operating member, 100 a link pivotally supporting the latter intermediate its ends and from the treadle support, a treadle pivotally mounted on the support, one end of said operating member terminating adjacent the treadle and being 105 detached therefrom, said treadle being adapted to engage and operate said operating member, a crank on the shaft, the other end of said operating member arching over the shaft and terminating adjacent the crank, 110 and means detachably connecting the end of said member with the crank, the last said means serving to hold all of the parts assembled and permitting the detachment of 115 said parts from the shaft when disconnected.

In testimony whereof I have signed my name to this specification, in the presence of two subscribing witnesses, on this 16th day of October A. D. 1909.

ROBERT J. BENNETT.
